FEED CONTROL FOR GANG SAWS

Julius Wegner, Flushing, N. Y.

Application June 21, 1947, Serial No. 756,124

14 Claims. (Cl. 125—16)

1

This invention relates broadly to stone sawing or cutting machines and more particularly to feeding mechanism for intermittently lowering or feeding the saw blades into the stone to be cut.

The structure of these sawing machines, called gang saws in the trade, usually consists of a frame, which carries a sash in which any number of saw blades from a few to a few hundred may be mounted. The sash frame may be operated in a number of different ways, such as, for instance, by means of a crank shaft and a connecting rod.

For the purpose of cutting through a stone slab, the sash frame, carrying the saw blades, is successively lowered. Heretofore, the lowering of the sash frame or the feeding of the saw blades into the stone has been accomplished either by a separate drive, which operated the feeding screws of the sash frame, or the feeding mechanism has been interconnected with the main drive of the machine, such as the crank shaft, thus operating the feeding screws intermittently by means of gear trains, ratchets, or similar arrangements. The drawback of the latter arrangement has been that the adjustment of the rate of feed has been very cumbersome and necessitated either shutting down these gang saws altogether, which, besides an inevitable loss of time, was likely to result in an uneven cut through the stone slab, or the operator had to climb up to the top of the gang saw in order to readjust the feed, which is an inconvenient as well as a dangerous task. Actuating the sash feed by means of gearing, ratchets, and the like, of course, limits the rate of feed to certain multiples of a given feed. Consequently, the operator would never adjust the most efficient feeding rate, and to prevent jamming the saw blades and doing other damage with too rapid a feeding rate, the operator has a natural tendency to set the feed of the sash frame at a slow enough rate to obviate these calamities under any and all circumstances.

The need has been felt in the trade for many years for a sash frame feed which could (1) be adjusted by the operator with convenience and without danger while the saw is in operation, and which (2) would allow a stepless adjustment of the feed to obtain maximum output regardless of the relative hardness of the stone to be cut.

The present invention overcomes the disadvantages previously described and answers fully the requirements of the trade in that the rate of

5 feed can be adjusted in infinite steps from minimum to maximum while the saw is in operation and from the regular working position of the operator, which is near the main drive of the gang saw.

The foregoing and other features of novel construction in the improved gang saw feeding mechanism will become apparent from the following description, taken in conjunction with the drawings, wherein:

Fig. 1 is a front elevation of a standard gang saw, in which the novel sash feeding mechanism is incorporated.

Fig. 2 is a plan view, showing the sash feeding mechanism depicted in Fig. 1 and part of the gang saw proper.

Fig. 3 is a fragmentary view in front elevation, illustrating a modification of the sash feed.

Fig. 4 shows the one-way clutches employed in the novel sash feed to a larger scale.

Fig. 5 is an enlarged fragmentary detail view in front elevation of sash frame adjusting screws, such as may be employed on each one of the four corners of a standard gang saw.

Fig. 6 is an enlarged sectional view of the feed control box mounted on the crank shaft.

Fig. 7 shows a view along line 7—7 of Fig. 6.

Fig. 8 shows a modification of the feed control in neutral position.

Fig. 9 illustrates the position of the device shown in Fig. 8 while the feeding rate is being decreased by reducing the eccentricity or crank throw.

Fig. 10 depicts the lower part of the slide of the modified feed control.

Figs. 11 and 12 show the split clamping ring in greater detail.

Gang saw proper

Referring to the general assembly shown in Figs. 1 and 2 of the drawings, the gang saw proper is illustrated more or less diagrammatically because it will be understood that the improved sash feeding mechanism may be used and adapted to any type of gang saw. The main frame of the gang saw is formed by vertical beams or columns 11, interconnected by cross beams 12. A sash frame or sash 13 of any conventional design is mounted in said main frame or main structure and may be horizontally guided by slides 14. Sash 13 may be reciprocated by any suitable means, such as connecting rod 19, pivotally secured to sash frame 13 and actuated by means of crankshaft 20, as shown. Crankshaft 50 20 carries flywheels 21 and 21A, which latter is

usually driven by flat belt or similar means by a prime mover, such as an electric motor (not shown).

As the sash frame 13, which may carry any required number of saws, is reciprocated, it is intermittently and progressively lowered to feed the saws into the stone to be cut. The means shown as an example comprise vertical, threaded spindles 16, which are journaled in bearings 15A, supported by the uprights 11 and guide plates 15 threaded on said spindles 16, which carry at their upper ends bevel gears 17 in mesh with bevel gears 17A on shafts 18. All spindles 16 are driven in synchronism by means of said bevel gears 17, 17A and additional bevel gears 17B, 15 when shaft 18 is rotated.

The gang saw, as briefly described above, is of altogether conventional design and does not form part of the present invention.

Sash frame feed

Feed control box 22, which is equivalent to an instantaneously adjustable crank, may be mounted at one end of crankshaft 20. A connecting rod 23 is provided to transmit the oscillating motion created by feed control box 22 to a crank arm 24, fast to an intermediate shaft 25, which may be mounted in bearings 26 and 27, supported either on the structure of the gang saw itself or on some auxiliary structure 28, formed by timbers or the like (Figs. 1, 2). A double crank arm 29, mounted in between bearings 26 and 27, is fastened to intermediate shaft 25, so that any oscillating movement of connecting rod 23 and crank arm 24, respectively, is transmitted to double crank arm 29. A bottom bar 30 and a top bar 31 transmit the oscillation of double crank 29 to cranks 32 and 33, respectively, which are secured to one-way clutches 37 and 38, respectively, mounted on clutch shaft 34, which is journaled in bearings 35 and 36, respectively, supported by the machine proper or by the auxiliary structure 28. Clutch shaft 34 also carries pinion 39, in mesh with gear 40 on main feed shaft 41. The latter is journaled in bearings 42 and 43. Gear 40, whose hub 44 may form one half of a jaw clutch, is freely rotatable on shaft 41, to which complementary clutch-half 45 is slidably keyed, so that member 45 may be brought into and out of engagement with clutch-half 44 by means of a hand lever or other suitable arrangement (not shown). Shaft 41 also carries fast and loose pulleys 46 and 47. These pulleys are arranged for rapid adjustment of the sash frame 13 in a vertical direction. A separate drive is generally used for this purpose, such as an electric motor with belt driving said pulleys 46 and 47. When employing this rapid feed, jaw-clutch 44-45 is in disengaged position (as shown in Fig. 2), thereby rendering the work feed from feed control box 22 inoperative. The rotation of shaft 41, whether caused by feed control box 22 or by said rapid height adjustment, is transmitted to the several shafts 18 of the machine proper by means of gear 48, fast to shaft 41, and pinion 49, fast to one of the feed shafts 18, as shown. As previously described, the sash frame 13 is thereby evenly lifted or lowered by means of vertical spindles 16. When the rapid height adjustment is not to be used, the belt is shifted to the loose pulley, thereby rendering this auxiliary rapid feed means inoperative.

It is pointed out that the previously mentioned one-way clutches 37 and 38 are of conventional design and can only impart clockwise rotation to shaft 34. Hence, when crank arm 29 moves in a

clockwise direction, clutch 38 will turn shaft 34 clockwise, while clutch 37, being simultaneously rotated counter-clockwise, is free-wheeling, and vice versa. It will be seen, therefore, that the feed screws 16 of the gang saw are operated during the forward stroke of the sash frame 13 as well as on its back stroke, thus imparting to the saws in sash frame 13 two downward feeding cycles for each reciprocating cycle of the sash frame 13. This double feed has proven very advantageous in cutting certain stones and has increased the cutting rate very appreciably.

If it is desired to impart to the sash frame only one feeding movement for each of its reciprocating cycles, bar 30 may be connected to a fixed point on the structure, as shown in Fig. 3. Thus one-way clutch 37 is rendered inoperative as regards imparting rotation to shaft 34 but will act as a brake to prevent any torsional springback of shaft 34, which might otherwise be caused by the elastic deformation in the various links of the feeding mechanism. It should also be observed that the free-wheeling clutch will act similarly during the double feed cycle. In other words, this design positively eliminates any undesirable torsional springback for the single as well as the double feed cycle. Feeding inaccuracies, such as found in conventional feed mechanisms, are done away with.

Feed control box

Feed control box 22, shown in Figs. 6 and 7, is adapted to be conveniently adjustable to produce any desired eccentricity from zero to maximum, while the gang saw is in operation.

The feed control mechanism is mounted in a housing 50, from which a suitable hub 51 extends for mounting on crank shaft 20 by means of set screws 52 or other suitable means. A hand wheel 53 is keyed and pinned to adjusting spindle 54, which is rotatably mounted in front in the hub-like projection 56 of slide 55 and is journaled in the rear in bracket 57A, suitably fastened to slide 55 by means of bolts or the like, as shown. Bevel gears 57 and 58 are fixedly mounted in spaced-apart relationship on spindle 54. In slide 55 a threaded adjusting screw 59 is journaled, which carries on its right-hand end bevel gear 60, located substantially centrally between bevel gears 57 and 58 when adjusting spindle 54 is in neutral position, as shown in Figs. 6 and 7. Screw 59 is in threaded engagement with wall 61 of the fixed inside structure 62, which consists of said transverse wall 61 and left and right members 63 and 64, respectively. This inside structure 62 is fixedly mounted with respect to the housing 50 and may be welded to the latter, as shown, or fastened to it by other suitable means. Slide 55 is provided at its front with shoulders 65, which guide feed slide 55 on corresponding shoulders 66 of sides 63 and 64 of inside structure 62.

The rear end 67 of spindle 54 extends into an elongated slot 68 of housing 50. In the neutral position of the feed control, which term will be more fully explained later, the end 67 of spindle 54 rests against the left-hand end of slot 68 (Fig. 6), thus providing a definite stop for spindle 54 towards the left. When spindle 54 is in its extreme right-hand position, further travel in this direction will be limited by the end 67 of spindle 54 coming in contact with the right-hand end of said elongated slot 68.

Slide 55 carries on its hub-like projection 56 a flanged, circular disc 69, whose shoulders 72 are adapted to slide on shoulders 70 and 71 of left and right-hand members 63 and 64, as shown.

Circular hub 73 of disc 69 is adapted to receive the right-hand end of connecting rod 23, which is free to oscillate on said hub 73. To keep the connecting rod end in place, a washer 14 is provided, which may be located against hub 73 by means of lock wheel 15, which is in threaded engagement with hub 56 of slide 55. It is pointed out that the thread on the end of hub 56 is a left-hand thread, because the crankshaft 20 usually revolves in a clockwise direction, as indicated in Fig. 6, so that the rotation of the crankshaft will have a tendency to tighten lock ring 15. It will be noted that, by tightening lock ring 15, slide 55 and the whole feed control mechanism will be locked in place, so that the eccentricity of disc 69 cannot vary or change, once lock ring 15 is tightened.

Feed adjustment

Fig. 6 shows the feed control mechanism in neutral position, that is, spindle 54 is in alignment with the axial center line of crankshaft 20. Feed disc 69, therefore, is concentric with the crankshaft 20, with the result that connecting rod 23 will remain stationary, hence the feed to the gang saw is zero. The hand wheel 53 will, of course, revolve, if not interfered with, as long as crankshaft 20 is revolving. Consequently, spindle 54 and bevel gears 57 and 60 will also revolve. They are, however, not in engagement with the teeth of bevel gear 60. Spindle 54 is provided with an annular groove 76 and slide 55 carries a spring-loaded ball 77 for the positive location of spindle 54 in its neutral position. If it is desired to increase the feed and, consequently, the stroke of the connecting rod 23, from zero to some larger value while crankshaft 20 is rotating with feed control box 22, lock ring 15 is loosened and hand wheel 53 pressed inwards and held stationary, thereby meshing bevel gears 57 and 60 to revolve screw 59. This screw, being right-hand and being mounted in the stationary inside structure 62, will cause the slide 55 to be moved to the right, thus bringing spindle 54 and stroke disc 69 in an eccentric position with regard to crankshaft 20. When the desired eccentricity is obtained, hand wheel 53 is pulled out into neutral position to disengage bevel gears 57 and 60, and the mechanism locked again by means of lock ring 15. Vice versa, to decrease the feed, hand wheel 53 is pulled toward the front after loosening lock ring 15, and bevel gears 57 and 60 are brought into engagement, thereby reversing the rotation of the adjusting screw 59 and moving the slide 55 towards the left. When the desired decreased eccentricity (and hence the corresponding stroke of connecting rod 23) is attained, spindle 54 is pushed into neutral position again, so that the gears are not in mesh, and lock ring 15 is locked.

As previously pointed out, the maximum travel of adjusting screw 59 and slide 55 is limited by the elongated slot 68, giving zero eccentricity when shaft end 67 rests against the left-hand wall, and maximum eccentricity when said shaft end 67 comes in contact with the right-hand wall of slot 68.

While bevel gears 57, 58 and 60 have been shown in this preferred embodiment of my invention, it will be understood that any other type of drive to actuate adjusting screw 59 could be employed, as, for instance, conical friction discs or similar devices.

While no scales for ascertaining the amount of feed adjusted by means of the feed control box 22 have been shown in the drawings, it is, of

course, understood that in practice a graduated scale with a suitable hand fastened to the slide 55 or component part thereof will be employed, to give the amount of feed adjusted in such units as are most practical.

Figs. 8 and 9 show a modification of the adjusting and locking mechanism of the feed box. In Figs. 6 and 7, a left-hand threaded locking ring 15 and washer 14 are shown to lock the slide 55 in its adjusted position. Figs. 8 and 9 show these members 14 and 15 replaced by an inner ring 18, outer ring 19, which together form a V-shape, as shown, cooperating with the inclined surfaces of a split ring 80 (Figs. 11 and 12), each half of which is provided with a pin 81. The bore of inner ring 18 possesses a sliding fit on hub 56. Outer ring 19 is in threaded engagement with the end of said hub 56 and may be locked to the latter by means of a set screw 82 and lead plug 83. To facilitate assembly of split ring 80, hub 56 may be slotted and said slots 84 may be closed with inserts 85 after assembly to leave a sliding fit for pins 81 (Fig. 10). The wedge angles on rings 18 and 19 and on ring 80 are so selected as to leave a clearance between the adjacent faces of rings 18 and 19 when assembled. Fig. 8 shows spindle 54 in neutral and locked position. In this position the ends of pins 81 rest against the full diameter of spindle 54. Both in front and back of this position, however, the diameter of spindle 54 is reduced for some distance, as shown in Figs. 8 and 9. Hence, when hand wheel 53 is pulled or pushed, the two halves of split ring 80 will collapse, because pins 81 are free to recede. Thus rings 18 and 19 are no longer wedged apart; consequently, slide 55 is also freed and may be moved into the desired position by screw 59, as explained before. Fig. 9 shows spindle 54 pulled out, thus meshing bevel gears 57 and 60 (Fig. 6) to decrease the crank throw or eccentricity of slide 55. To impart rotation to bevel gear 60, hand wheel 53 must be held stationary while crankshaft 20 is rotating, as previously explained in connection with Figs. 6 and 7. The modification shown in Figs. 8, 9, 10, 11, 12 will clamp slide 55 in its adjusted position without a threaded lock ring, such as 15, Fig. 6. It, therefore, still further simplifies changing the adjustment of the feeding rate while the gang saw is in operation.

The feed box has been shown mounted directly on the end of the crankshaft 20 of the main drive. It is obvious that this is not an essential part of my invention, as the feed box may be mounted on any synchronously rotating member of a machine and the linkage mechanism changed accordingly.

The advantages of my infinitely variable single and double feed have been shown in connection with a gang saw for parting or sawing stone, but it will be understood that this same device may also be used in connection with other equipment requiring a similar feed which is adjustable while in operation.

While I have shown and described, by way of example, mechanism for attaining the stated objects, I wish to have it understood that various changes or modifications may be made within the scope of the claims hereto attached without departing from the spirit of the invention.

What I claim is:

1. In a machine for parting stone blocks and the like, a multiplicity of saw blades, a sash for mounting said blades, a structure to suspend said sash, means for actuating said sash relative to said structure, adjusting means for lowering said sash to feed said saw blades progressively into

the stone block, two one-way clutch mechanisms for alternately actuating said sash adjusting means, and feed control means operatively connected with said two one-way clutch mechanisms, said feed control means having adjustable stroke means associated therewith for changing the rate of feed.

2. In a machine for parting stone blocks and the like, a multiplicity of saw blades, a sash for mounting said blades, a structure to suspend said sash, means for actuating said sash relative to said structure, adjusting means for lowering said sash to feed said saw blades progressively into the stone block, two one-way clutch mechanisms for alternately actuating said sash adjusting means, and feed control means operatively connected with said two one-way clutch mechanisms, said feed control means having adjustable stroke means associated therewith for changing the rate of feed while the machine is in operation, and locking means for locking said adjustable stroke means in its adjusted position.

3. In a machine of the character described, a multiplicity of saw blades, a sash for mounting said blades, a structure to suspend said sash, means for reciprocating said sash relative to said structure, means for adjusting said sash vertically to feed said saw blades progressively into the work material, two one-way clutch mechanisms for alternately actuating said sash adjusting means in synchronism with the reciprocating movement of the sash, said one-way clutch mechanisms being adapted to alternately lock said sash adjusting means against torsional spring-back during part of their operating cycle, feed control means operatively connected with said two one-way clutch mechanisms, said feed control means having adjustable stroke control means associated therewith for changing the rate of feed.

4. In a gang saw for parting stone blocks and the like, a sash, means for reciprocating said sash, further means for adjusting said sash in vertical direction, two one-way clutch mechanisms for actuating said adjusting means, and a feed control device adapted to actuate said two one-way clutches in synchronism with the reciprocating movement of said sash.

5. In a gang saw for parting stone blocks and the like, a sash, means for reciprocating said sash, further means for adjusting said sash in vertical direction, two one-way clutch mechanisms operatively connected with said sash adjusting means, a feed control device for actuating said two one-way clutch mechanisms in synchronism with the reciprocating movement of said sash, one of said one-way clutch mechanisms being adapted to actuate said adjusting means during the forward swing of the sash and the other one-way clutch mechanism being adapted to actuate said adjusting means during the return swing of said sash.

6. In a gang saw for parting stone blocks and the like, a sash, means for reciprocating said sash, further means for adjusting said sash in vertical direction, two one-way clutch mechanisms operatively connected with said sash adjusting means, a feed control device for actuating said two one-way clutch mechanisms in synchronism with the reciprocating movement of said sash, said one-way clutch mechanisms being adapted to actuate said sash adjusting means alternately during the forward and return swings of said sash and to lock said sash adjusting means

against torsional spring-back during the remainder of their respective operating cycles.

7. In a machine of the character described, a sash frame, a crankshaft operatively connected to said sash frame to reciprocate the latter, means for adjusting said sash frame in vertical direction, two one-way clutch mechanisms for alternately actuating said adjusting means, a feed control device operatively connected to said clutch mechanisms comprising a housing for mounting on said crankshaft to rotate said feed control device in synchronism with said reciprocating sash frame, an adjustable slide in said housing acting as a crank, a screw adjusting mechanism for said slide, means for rotating said screw adjusting mechanism in either direction for increasing or decreasing the eccentricity of said slide while the crankshaft is rotating, and means for locating and locking said rotating means in inoperative position.

8. In a stone cutting machine having a plurality of saw blades mounted in a reciprocating sash frame, means for moving said sash frame in vertical direction for feeding the saw blades into the stone block, including a control device adapted to be adjusted while said sash frame reciprocates, two one-way clutch mechanisms operatively connected with said control device and said sash frame adjusting means for alternately actuating the latter, said one-way clutch mechanisms being also adapted to lock said sash frame adjusting means against torsional spring-back during part of the operating cycle, and threaded means for locating said control device in its adjusted position.

9. A feed control device of the character described, means for rotating said device in synchronism with the operation of a machine, said feed control device comprising a slide producing a crank motion, means for displacing said slide eccentrically to increase or decrease its throw while said feed control device is rotating, and wedge-like locking means for maintaining said slide in displaced position.

10. In a gang saw for cutting stone blocks and the like, a sash frame, saw blades mounted in said sash frame, a crankshaft operatively connected to said sash frame to reciprocate the latter, a feed control device comprising a housing for mounting said device on the crankshaft to rotate said device in synchronism with said sash frame, an adjustable slide in said housing producing a crank motion, threaded means associated with said slide adapted to displace said slide, actuating means for said threaded means for increasing or decreasing the eccentricity of said slide while said crankshaft and said feed control device are rotating, means for locating said actuating means in an inoperative position, and further means for locking said actuating means in said inoperative position and for simultaneously locking said slide in its adjusted position.

11. In a machine of the character described, a multiplicity of saw blades, a sash for mounting said blades, a structure to suspend said sash, means for reciprocating said sash relative to said structure, means for adjusting said sash vertically to feed said saw blades into the work material, ratchet means for actuating said sash adjusting means, other ratchet means for locking said sash adjusting means against torsional spring-back, a feed control device for actuating said first ratchet means, means for rotating said feed control device in synchronism with the reciprocating sash frame, said feed control device comprising

a slide producing a crank motion, means for displacing said slide eccentrically to increase or decrease its throw while said feed control device is rotating, and locking means for maintaining said slide in displaced position.

12. Mechanism for progressively feeding the reciprocating sash frame of stone cutting saws towards the work material comprising a control device, means for rotating said control device in synchronism with the reciprocating sash frame, said control device including a slide producing a crank motion, means for displacing said slide eccentrically to increase or decrease its throw while said control device is rotating, locking means for maintaining said slide in displaced position; two ratchet mechanisms operatively connected with said slide and adapted to feed the sash frame towards the work material in synchronism with the reciprocating movement of the latter.

13. In a feed control device, means for rotating said device in synchronism with the operation of a machine, said feed control device comprising means for producing a crank-motion, other means for displacing said crank-motion producing means eccentrically to increase or decrease its throw while said feed control device is rotating, and auxiliary means for maintaining said crank-motion producing means in displaced position.

14. A feed control device, means for rotating said device in synchronism with the operation of a machine, said feed control device comprising a housing, a slide associated with said housing for producing a crank motion, a spindle in threaded engagement with said housing and adapted to actuate said slide to displace the latter eccentrically to increase or decrease its throw, a drive shaft rotatably mounted in said slide at substantially a right angle relative to the axis of said spindle, cooperating driving means mounted on said spindle and on said drive shaft adapted to selectively rotate said spindle in either one of two directions while said feed control device is rotating, and auxiliary means for locking said slide in displaced position.
